by The Firm of Charlesworths & Atty's.

UNITED STATES PATENT OFFICE

166,504

DECIMAL CHART OR SIMILAR ARTICLE

John Harold Slingerland, Wheaton, Ill., assignor
to Central Steel and Wire Company, Chicago,
Ill., a corporation of Illinois

Application September 15, 1949, Serial No. 5,018

Term of patent 3½ years

(Cl. D59—2)

To all whom it may concern:

Be it known that I, John Harold Slingerland, a citizen of the United States, and a resident of the city of Wheaton, in the county of Du Page and State of Illinois, have invented a new, original, and ornamental Design for a Decimal Chart or Similar Article, of which the following is a specification, reference being had to the accompanying drawing, forming a part thereof.

On the drawing:

The figure is a plan view of a decimal chart or similar article, showing my new design, the back being plain and the article being of no substantial thickness.

I claim:

The ornamental design for a decimal chart or similar article, as shown and described.

JOHN HAROLD SLINGERLAND.
